(57) **CLAIM**

The ornamental design for a ceramic bonding tool with textured tip, as shown and described.

DESCRIPTION

FIG. 1 depicts a perspective view of a ceramic bonding tool with textured tip.

FIG. 2 depicts a side elevation view of the ceramic bonding tool with textured tip of FIG. 1.

FIG. 3 depicts a top plan view of the ceramic bonding tool with textured tip of FIG. 1.

FIG. 4 depicts a bottom plan view of the ceramic bonding tool with textured tip of FIG. 1.

FIG. 5 depicts detailed side elevation view of the ceramic bonding tool with textured tip of FIG. 1.

FIG. 6 depicts a detailed bottom plan view of the ceramic bonding tool with textured tip shown in FIG. 4.

FIG. 7 depicts a detailed side cross-sectional view of the ceramic bonding tool with textured tip, the cross-section taken along cross-section indicator line 7-7 of FIG. 6.

The broken lines in the drawings illustrate environmental structure on the article and form no part of the claimed design.
